UNITED STATES PATENT OFFICE.

HERBERT H. LEDERER, OF CLEVELAND, OHIO.

CUFF.

1,387,854.

Specification of Letters Patent. Patented Aug. 16, 1921.

Application filed December 18, 1918. Serial No. 267347

To all whom it may concern:

Be it known that I, HERBERT H. LEDERER,
a citizen of the United States, residing at
Cleveland, in the county of Cuyahoga and
5 State of Ohio, have invented a certain new
and useful Improvement in Cuffs, of which
the following is a full, clear, and exact de-
scription, reference being had to the accom-
panying drawings.

10 This invention relates to cuffs of the folding type and has for its object to provide a double cuff of this type each member of which may conveniently serve as a cover for the other, thus enabling the shirt to be
15 used for a period of time corresponding to the soiling of both cuff members. I realize the foregoing object in a particularly efficient and economical manner in and through the construction and arrangement of parts
20 illustrated in the drawings forming a part hereof wherein:—Figure 1 represents an elevation of the interior of a sleeve having my cuff applied thereto; Fig. 2 a similar view showing the manner in which the inner cuff
25 member may be drawn through the outer cuff member so as to be covered by the outer member; Fig. 3 a sectional view of the parts shown in Fig. 1; Fig. 4 a sectional view showing the positions of the cuff members
30 when folded up to form a double folded cuff with the inner member covering the outer member; Fig. 5 a view similar to Fig. 3 showing the cuff members reversed; Fig. 6 a view similar to Fig. 4, showing the cuff
35 members of Fig. 5 in folded position; Figs. 7 and 8 are elevations, similar to Figs. 1 and 2, respectively, and showing a modification of the invention; and Figs. 9, 10, 11 and 12 are sectional views of such modification
40 with the cuff members in the positions shown respectively in Figs. 3, 4, 5 and 6.

Describing the various parts herein by reference characters, 1 denotes the sleeve of a shirt, the same being shown as open at its lower end and having attached to the bottom thereof a soft cuff member 2 having a transverse slit 3 through the upper central portion thereof. The cuff member 2 is provided with the button holes 4.

50 5 denotes an inner cuff member having at its central portion a tab 6 by which said member is secured to the outer cuff member above the slit 3 therein. This tab is preferably of slightly less length than the length 55 of the slit 3, and the unattached upper edges 7 of said member are preferably inclined

downwardly toward the side edges thereof to facilitate the passing of the inner member through the slit in the outer member. When in unfolded condition and with the parts arranged in the positions shown in Fig. 1, the bottom of the inner cuff member will preferably extend a slight distance below the outer member so that, when both members are folded outwardly, as shown in Fig. 4, the upper ends will be substantially flush with each other and the inner member will provide a cover for the outer. The inner member is also provided with button holes 8 which are adapted to register with the 70 button holes 4 when the said members are folded.

When the inner member has become soiled, the cuff buttons may be removed and the said inner member may be passed through the slit 3 in any convenient manner, as indicated for instance in Fig. 2. The positions of the parts when the inner member has thus been passed or drawn through the slit are shown in Fig. 5. The passing of the inner member through the slit in the outer member will reduce the effective length of the former member so that the lower end thereof will ordinarily be no lower than, and preferably a short distance above, the lower end of the outer member. Both members may then be folded outwardly in the manner shown in Fig. 6 and the cuff buttons inserted in the usual manner.

In Figs. 7 to 12 inclusive there is shown a modification which differs from the construction shown in Figs. 1 to 6 inclusive mainly in that the inner member 5^a is secured to the outer member 2^a a short distance below the slit 3^a in said outer member. In both forms of the invention, the inner cuff member is secured to the outer cuff member (preferably by stitching) adjacent to the slit in the outer member; and in both forms of the invention, the top of the inner cuff member is preferably inclined downwardly toward the side edges thereof to facilitate the passage of the inner member through the slit.

The button holes are so arranged in both modifications that, when the cuff members are folded, the button holes in one member may be conveniently brought into such register with the button holes in the other member as will facilitate the application of the cuff buttons. 105 110

Having thus described my invention, what I claim is:

1. The combination, with a shirt sleeve, of a foldable cuff member having a slit whose periphery lies entirely within the cuff body below the upper portion thereof, said cuff member being connected along substantially its entire upper portion, above the upper periphery of said slit, to the sleeve, and a second foldable cuff member having a tab at its upper end secured to the first member adjacent to the said slit.
- 10 2. The combination, with a shirt sleeve,

of a foldable cuff member having a slit whose periphery lies entirely within the cuff body 15 below the upper portion thereof, said cuff member being connected along substantially its entire upper portion, above the upper periphery of said slit, to the sleeve, and a second foldable cuff member having a tab at 20 its upper end secured to the first member below said slit.

In testimony whereof, I hereunto affix my signature.

HERBERT H. LEDERER.
